METHOD OF MAKING ALKYLDIHYDRO-
THEBAINONES

Frank C. Whitmore, State College, Pa., and August H. Homeyer, Webster Groves, Mo., assignors to Mallinckrodt Chemical Works, St. Louis, Mo., a corporation of Missouri

No Drawing. Application May 3, 1946,
Serial No. 667,108

9 Claims. (Cl. 260—285)

1

This invention relates to the manufacture of narcotics and more particularly to methods for the preparation of intermediates for the manufacture of methyldihydromorphinone.

Among the objects of this invention are the provision of methods for the utilization of by-products in the manufacture of derivatives of the morphine series; the provision of methods for improving the yield of desired products in the manufacture of derivatives of the morphine series; and the provision of methods for more easily preparing intermediates for the manufacture of methyldihydromorphinone. Other objects will be in part apparent and in part pointed out hereinafter.

The invention accordingly comprises the steps and sequence of steps, and features of synthesis, analysis, or metathesis, which will be exemplified in the processes hereinafter described, and the scope of the application of which will be indicated in the following claims.

In the manufacture of methyldihydromorphinone one of the intermediates customarily utilized is methyldihydrothebainone. This intermediate may be prepared from thebaine by hydrogenation to dihydrothebaine, followed by reaction with a Grignard reagent to form methyldihydrothebainone. It has been found, however, that on hydrogenation of thebaine, relatively small quantities of dihydrothebaine are obtained together with larger quantities of dihydrothebainone.

Dihydrothebainone has been of limited utility because to convert it to the desired methyldihydrothebainone it has been necessary to first form dihydrocodeinone, then the acetate of the enol form of dihydrocodeinone, and then to form the desired methyl derivative, methyldihydrothebainone.

In accordance with the present invention, however, it has been found that dihydrocodeinone can be directly converted to methyldihydrothebainone without the intermediate formation of the acetyl derivative of the enol form of dihydrocodeinone. The overall yield of methyldihydrothebainone obtained in accordance with the present invention from dihydrocodeinone is considerably better than obtained from indirect previous methods.

Dihydrocodeinone can, of course, be prepared in various ways. One source, as has been mentioned, is the by-product dihydrothebainone, which is obtained in the hydrogenation of thebaine to form dihydrothebaine. Dihydrocode-

inone can, as is known, also be made from other materials such as codeine or dihydrothebaine.

In accordance with the present invention dihydrocodeinone is reacted with a Grignard reagent such as a methyl magnesium halide to form methyldihydrothebainone. This reaction may be carried out to give high yields of the desired product. In this way the previously utilized complex processes for converting dihydrocodeinone to methyldihydrothebainone by formation, for example, of the acetyl derivative of the enol form of dihydrocodeinone, followed by reaction of this product with a Grignard reagent, are materially shortened and improved.

15 The following examples illustrate the invention:

Example I

Two moles of methyl magnesium iodide solution (1310 cc. of 1.53 N) was distilled in a 5 liter, three-necked flask fitted with a mercury sealed stirrer, dropping funnel and condenser, until no more ether came over with the bath at about 100° C. One liter of dry benzene was added to the residue, stirred, and heated to boiling, while a solution of 200 g. of dihydrocodeinone in 2 liters of dry benzene was added during 10 minutes. Distillation was continued by heating until 800 cc. of distillate were collected. Then the condenser was set for refluxing which was continued for 15 six hours. A voluminous white solid formed during the addition of the dihydrocodeinone to the Grignard reagent. At the end of the reaction, the complex was decomposed by adding to the flask excess dilute hydrochloric acid (about 350 cc. concentrated hydrochloric acid diluted to 2 liters) and the benzene layer was separated and washed with dilute hydrochloric acid which was added to the main aqueous phase. The aqueous phase was stirred with 1 liter of chloroform and made ammoniacal by adding a small excess of ammonia containing a few grams of sodium hydrosulfite. The aqueous phase was re-extracted with four 500 cc. portions of chloroform and the combined extracts were distilled to dryness. The residue of crude methyldihydrothebainone weighed 167 g. and was dissolved in 460 cc. of anhydrous alcohol. Hydrogen chloride gas was passed into the solution until it was strongly acid and the hydrochloride of methyldihydrothebainone separated in crystalline form. The first crop of crystalline, dry hydrochloride weighed 111 g., or 47% of the theoretical yield.

Example II

55 An ether solution of 206 cc. of methyl mag-

nesium bromide containing 0.4 mole was concentrated by distillation in a water bath until no more ether would distill. 270 cc. of dry benzene was added and the condenser was arranged for refluxing. After bringing to refluxing temperature, a warm solution of 40 grams of dihydrocodeinone in 700 cc. of dry benzene was added during 18 minutes. The solution was stirred and refluxed for one and one-half hours and then was refluxed without stirring for four and one-half hours more. A test for the presence of a Grignard reagent was negative. The reaction mixture was decomposed by addition of excess dilute hydrochloric acid and then the solution was made alkaline with ammonia, and a little sodium hydrosulfite, $\text{Na}_2\text{S}_2\text{O}_4$, was added. The benzene layer was separated and the water layer was extracted three times with chloroform. The benzene and chloroform extracts were combined, dried, and concentrated by distillation, the last traces of solvent being removed under reduced pressure. The residue, weighing 32.5 grams, was dissolved in 60 cc. of anhydrous alcohol and the solution was saturated with hydrogen chloride. A precipitate formed immediately and after storing in a refrigerator overnight, it was filtered off and washed with alcohol. The dry methyldihydrothebainone hydrochloride weighed 15.5 grams.

In the foregoing examples other methyl magnesium halides may be substituted for the methyl magnesium iodide and methyl magnesium bromide respectively described.

Example III

12 grams of impure methyldihydrothebainone was suspended in 100 cc. of water and dissolved by adding hydrobromic acid until all the solid was in solution and the solution was acid to Congo. The solution was decolorized with activated carbon and allowed to crystallize. The crystals of methyldihydrothebainone hydrobromide after drying weighed 12.6 grams.

Example IV

72.5 grams of crude methyldihydrothebainone hydrochloride was dissolved in 300 cc. of hot water, decolorized with activated carbon and after filtering, 40 grams of sodium bromide was added. Methyldihydrothebainone hydrobromide crystallized rapidly. After cooling it was filtered off and washed with alcohol. The slightly moist hydrobromide weighed 71 grams.

As shown in these examples the hydrobromide of methyldihydrothebainone can be prepared by reacting the alkaloid with hydrobromic acid or it can be formed by treating the hydrochloride of the alkaloid with a bromide salt. The hydrobromide is of particular value. For example, it has more desirable solubility characteristics than the hydrochloride, and is accordingly of a special utility for purifying the alkaloid.

It will be understood, of course, that homologs of methyldihydrothebainone may be prepared in an analogous manner by using an appropriate Grignard reagent.

The extraction of the crude methyldihydrothebainone is advantageously carried out by the use of chloroform as indicated in the foregoing examples. Chloroform is not only an effective solvent for this purpose, but it has certain advantages over the previously utilized solvents. For example, extraction with ether is hazardous and clumsy on account of the large volumes of solvent required. Extraction with benzene has a tendency to form stubborn emulsions. Chloro-

form as a solvent for this purpose is not subject to the foregoing disadvantages. Relatively small proportions of chloroform are effective to extract the methyldihydrothebainone efficiently from its aqueous solution.

In view of the above, it will be seen that the several objects of the invention are achieved and other advantageous results attained.

As many changes could be made in the above processes without departing from the scope of the invention, it is intended that all matter contained in the above description shall be interpreted as illustrative and not in a limiting sense.

We claim:

- 15 1. The method of making an alkyldihydrothebainone which comprises adding dihydrocodeinone to a Grignard reagent selected from the group consisting of an alkyl magnesium bromide and an alkyl magnesium iodide in an aromatic solvent.
- 20 2. The method of making methyldihydrothebainone which comprises adding dihydrocodeinone in an aromatic solvent to a methyl Grignard reagent selected from the group consisting of a methyl magnesium bromide and a methyl magnesium iodide in an aromatic solvent.
- 25 3. The method of making methyldihydrothebainone which comprises adding dihydrocodeinone to a methyl Grignard reagent selected from the group consisting of a methyl magnesium bromide and a methyl magnesium iodide in benzene.
- 30 4. The method of making methyldihydrothebainone which comprises adding dihydrocodeinone in benzene to a methyl Grignard reagent selected from the group consisting of a methyl magnesium bromide and a methyl magnesium iodide in benzene.
- 35 5. The method of making methyldihydrothebainone which comprises removing the major portion of the solvent ether from an ethereal solution of a methyl Grignard reagent selected from the group consisting of a methyl magnesium bromide and a methyl magnesium iodide, adding an aromatic solvent to said Grignard reagent and then adding dihydrocodeinone.
- 40 6. The method of making methyldihydrothebainone which comprises adding a benzene solution of dihydrocodeinone to a benzene solution of a methyl magnesium halide selected from the group consisting of a methyl magnesium bromide and a methyl magnesium iodide, decomposing the complex formed by adding excess dilute hydrochloric acid, extracting the methyldihydrothebainone with chloroform, purifying the product by forming a hydrohalide of the methyldihydrothebainone.
- 45 7. The method of making an alkyldihydrothebainone which comprises reacting dihydrocodeinone with a Grignard reagent selected from the group consisting of an alkyl magnesium bromide and an alkyl magnesium iodide in an aromatic solvent.
- 50 8. The method of making an alkyldihydrothebainone which comprises reacting dihydrocodeinone with an alkyl magnesium bromide and an aromatic solvent.
- 55 9. The method of making an alkyldihydrothebainone which comprises reacting dihydrocodeinone with alkyl magnesium iodide and an aromatic solvent.
- 60 10 70 65 75 80 85 90 95
